UNITED STATES PATENT OFFICE.

GEORGE A. TAYLOR, OF WEEHAWKEN, NEW JERSEY, ASSIGNOR TO NATIONAL BISCUIT COMPANY, OF NEW YORK, N. Y., A CORPORATION OF NEW JERSEY.

DESIGN FOR A COVER FOR CONTAINERS.

Application filed September 8, 1921. Serial No. 499,343. Term of patent 14 years.

To all whom it may concern:

Be it known that I, GEORGE A. TAYLOR, a citizen of the United States, residing at Weehawken, in the county of Hudson and State of New Jersey, have invented a new, original, and ornamental Design for a Cover for Containers, of which the following is a specification, reference being had to the accompanying drawing, forming part thereof.

In the drawing Fig. 1 is a front elevation and Fig. 2 is a top plan view of a cover for containers showing my new design.

I claim—

The ornamental design for a cover for containers, as shown.

GEORGE A. TAYLOR.
